MARINE ICE PLANT

James A. Bonnington, Washington, D. C., and
Hulon O. Warlick, Jr., Arlington, Va.

Application May 21, 1948, Serial No. 28,438

4 Claims. (Cl. 114—5)

1

This invention relates to refrigeration and the production of ice, and more particularly to a self-contained, mobile, ice manufacturing plant.

The invention particularly contemplates the installation of an ice manufacturing plant aboard ship, or in other words a marine ice plant.

Heretofore when ice has been required it has been customary to obtain the same from a fixed location. Frequently it has become desirable to have ice at a particular location, which may or may not have justified year-round facilities for producing such ice at that location.

It is an object of the present invention to provide a mobile, self-contained ice manufacturing plant which can be used in a particular location as long as it is necessary or desired, and can be readily moved to another vantage point when the occasion arises.

Some of our industries are very seasonal and for a relatively short period require large quantities of ice, while for relatively long periods no ice or a substantially small amount of ice is required. In some warmer climates a particular harvest of perishable crops may make it desirable to have an abundance of ice in a relatively short time.

The installation on a marine vessel of an ice manufacturing plant likewise presents certain problems, including those of distribution of weight, the most efficient arrangement of equipment for maximum utilization of space within the limits and confines of the vessel, the arrangement of the parts to have them freely accessible, the provision of necessary ice storage facilities, the complete freezing, dumping of ice cans, the preventing of excessive movement of fluid used in conjunction with the system including brine, compensation for the ship's movement including rolling, the cooling of the heat-emitting parts of the system, the heating of parts for facilitating ice removal, the novel use of fluid ballast contained in the bilges in keeping the ship steady, and the like.

Further objects and advantages of the invention will be apparent from the following description taken in conjunction with the accompanying drawings, wherein:

Fig. 1 is a top plan view of a vessel from amidships aft, containing an ice manufacturing installation, the main and top decks being removed for purposes of installation;

Fig. 2, a similar view of a vessel from amidships forward of the vessel of Fig. 1, with the top deck partially broken away and the roof of the deck house omitted;

Fig. 3 is a side elevation of amidships aft with the starboard side omitted to reveal the ship's interior;

Fig. 4, a side elevation of amidships forward with parts broken away to reveal the ship's interior;

Fig. 5, a perspective of a dump for ice cans and

2

a dip tank for melting ice so that it can be removed from the can in which it is contained;

Fig. 6, a perspective of a pair of dip tanks and the associated piping by means of which warm condenser water is admitted and an overflow permitted to be discharged;

Fig. 7, a perspective of an ice chute for transferring cakes of ice from an upper to a lower deck;

Fig. 8, an enlarged fragmentary detail perspective of the actuating means for the switchgate of Fig. 7;

Fig. 9, a top plan view of the structure of Fig. 7;

Fig. 10, a diagrammatic detail of ship-steadying means used in conjunction with the present invention, and

Fig. 11, a fragmentary sectional view illustrating the cooling means for the cold storage rooms and the connections to the brine pump permitting utilization thereof for multiple purposes.

With continued reference to the drawings, the character of the vessel on which the ice plant is installed is dependent upon numerous factors. However, as illustrated in the drawings a vessel which is relatively strong and seaworthy, is readily adaptable for use in very shallow water as, for example, a type of vessel used for landing troops on beachheads and in shallow water. As shown the vessel consists of a bow 10, a stern 11, a starboard side 12, and a port side 13.

Figs. 1 to 4 are largely schematic in nature and are intended to show the arrangement of the various elements and machines within the hull of the vessel. Figs. 1 and 2 show such arrangement in plan and Figs. 3 and 4 in elevation, the latter two figures not being true sectional views, but merely having the starboard side of the vessel removed. Figs. 2 and 4 are not exact continuations of Figs. 1 and 2 there being a portion of the amidships section omitted since this is not considered necessary to a full understanding of the invention.

Control of the vessel may be accomplished from a pilot house 14 having a hurricane bridge 15. The vessel is equipped with twin rudders 16 and a steering engine 18 for steering the same, twin screws or propellers 17 for driving or producing motion of the vessel. The screws of propellers and rudders are protected by skegs 18.

The aforementioned parts are partially in the hollow tunnel stern 19 of the vessel, thereby allowing it to traverse shallow waters. The hollow tunnel stern 19 is an integral part of the ship's bottom 20 and also aids in floating the ship, when aground, by creating a large wave or swell, when reversing the engines of a size large enough to wash the sand away and float the ship.

The screws or propellers 17 are driven through propeller shafts 21 from twin sets of power or propelling engines 22 which serve the dual purpose of driving the vessel and operating refriger-

ation equipment. The power-propelling engines 22 are each 220-horsepower diesels from which there is a power takeoff shaft 23 which drives a countershaft 24 by means of a series of V-belts 25 running over pulleys 26 and 27. The countershaft 24 is used to drive a ship's generator 22 and an ammonia or other refrigerant compressor 29 by means of V-belts 30 and 31 running on pulleys 32, 33, 34 and 35, respectively. The shafts 23 and 24 are mounted in suitable bearings 36 and 37 of conventional construction.

The refrigeration and ship's machinery are housed in two compartments 38 and 39 which comprise the ship's engine rooms located in the aft end of the vessel, and below the main deck.

The ship is provided with an auxiliary generator 40 which may be used in the event of the breakdown of the main system. Also enclosed in compartment 38 is a fire and bilge pump 41 which may be used in event of fire aboard ship or in trimming or levelling the ship at anchor. Within the compartment 39 is housed a compressor 42 of a smaller ice plant which also includes a condenser 43. From the condenser 43 a pipe 44 extends forwardly of the vessel and serves to conduct warm condenser water into port and starboard dip tanks 45 and 46, respectively. These dip tanks are provided with overflow pipes 47 located substantially midway of the height of the tanks, the pipes 44 entering the tanks nearer their bottoms. Associated with the dip tanks 45 and 46 are port and starboard can dumps 48 and 49, respectively, which are used to discharge ice from the cans 50 in which it is manufactured.

The can dumps are identical, consequently we will describe can dump 48 which consists of a rectangular receptacle open at its upper end and mounted on a pair of spaced A frames 51, and pivoted at 52. If desired the A frames may be supported on elevating blocks 53.

From the can dumps 48 and 49 ice is directed to desired locations, as for example through a door opening 54 closed by an insulating door 55 in the insulated wall 56 of a cold storage compartment 57 located below the main deck 58. In its travel from the port can dump 48 the cake or block of ice is discharged onto an operating platform or deck 59; thence it passes through the door opening 54 down through chute 60, along chute 61, through the gate 62 loaded by means of a spring 62', up the chute 63 and down chute 64 into the storage compartment 57. In the after end of the cold storage compartment 57 is provided a service door 65 for ready access to the interior of this compartment.

An ice crusher 66 is located in the forward end of the cold storage compartment 57 and crushed ice is transferred or conveyed from this compartment in the vicinity of the crusher by means of a conveyor 67 which travels on pulleys 68 and 69 driven by a motor 70 by means of a V belt 71.

Crushed ice is discharged from the conveyor 67 into the cold storage and unloading room 72 in which room ice in cake or other form is stored for convenient disposition either for unloading or subsequent other use. Ice may be removed or unloaded from the cold storage and unloading room 72 through a door 73 onto a dock or other vessel. On the bridge or top deck 74 there is mounted a small ice machine 75 having a chute 76 through which small particles of ice may be discharged into the cold storage and unloading room 72, the small ice machine 75 being prefer-

ably enclosed in a housing or room 77. The ice discharged from the small ice machine through the chute 76 is collected in a bin 78 for containing the ice for subsequent use. The ice within the storage bin 78 consists of smaller particles than that produced by the crushing operation and is for different uses. The smaller ice may be used in drinks, while the crushed ice may be used in connection with the shipping of fish, in soda fountains or the like.

The large ice plant on the vessel in addition to the compressor 29 driven from the main power plant of the vessel, includes an evaporative condenser 80 to which the condensed refrigerant is supplied through pipes not shown. The condensed refrigerant from the condenser 80 is supplied to refrigerating coils 81 which serve to refrigerate the brine in the refrigerating tank 82 sufficiently to reduce temperature in the ice cans 50 submerged therein to cause the ice to form, or in other words, the water in the cans to congeal into ice. The ice cans 50 are lowered into and elevated from the freezing tank 82 by means of cables 83 on a monorail hoist 84 which travels transversely of the vessel on a single rail 85 and travels longitudinally of the vessel on spaced rails 86.

The vessel is provided with conventional port and starboard bilge compartments 87 and 88, these compartments being normally empty. However, certain of these are partially filled with liquid in the present instance and this liquid is transported from one portion of the vessel to the other from the port to the starboard side or vice versa as needed for proper balance. The transfer of liquid from the port to the starboard side or vice versa is accomplished by means of a gear pump 89 which draws liquid through one of its pipes 90 or 91 and discharges liquid through the other. In other words, the suction side of the pump may draw in liquid through the pipe 90 from the port side of the vessel and discharge the same into the starboard side or remove the liquid from starboard bilges and discharge the same into port bilges.

In order to control the operation of the pump which may be a conventional gear pump in accordance with the needs of the vessel or the load contained thereon, the pump may be driven by a reversible motor 92 and in cooperation with a control stabilizer. The stabilizer consists of a housing 93 and a pendulum 94 having an adjustable collar or weight 95 thereon, the adjustment of which serves to shorten or lengthen the pendulum to change its rate of oscillation. The pendulum 94 is mounted on a pivot 96 in the upper end of the housing 93. To the upper end of the pendulum is fixed a pair of circuit forming conductors 97, one of which is connected to an adjustable contact 98 in the housing 93. When the ship lists to port, the housing 93 will move therewith and cause contact 98 and the pendulum to engage thus completing through the motor 92 to operate the pump 89. A similar circuit contact 99 is disposed on the opposite or starboard side of the housing 93 and when the ship lists to starboard a like circuit is completed through the motor causing it to rotate in the reverse direction; consequently due to the resulting transfer of ballast the ship will be maintained stabilized. When the ship is in a level position the pendulum will be suspended in spaced relation between each of the contacts 98 and 99 and the pump 89 will be inoperative.

In Fig. 11, there are shown the various con-

nections by means of which a brine circulating pump 100 may be used for multiple operations. The pump 100 is connected to the brine tank 82 at a point adjacent the cooling coils 81 by means of a conduit 101.

A discharge conduit 102 is connected to the pump 100 and leads to a cooling coil 103 disposed in the storage room 57. Coil 103 is connected in series with a similar coil 104 disposed in the storage room 72. The brine in the coil 104 is allowed to return to the tank 82 from the tank 72 through a conduit 105.

During operation of the plant, frost will form on the coils 103 and 104 and from time to time it is necessary to remove this frost in order to maintain the efficiency of the plant. This defrosting process may be accomplished in several ways but is preferably carried out by circulating relatively warm water through the coils to melt the frost. This water may be obtained from several sources, one of which may be the water usually present in the bilge of the ship. For this purpose a pipe 106 is connected to the pump intake conduit 101, pipe 106 leading to a low point in the bilge. Valves 107 and 108 are provided respectively in the pipe 106 and in the intake conduit 101 for controlling flow therethrough.

When it is desired to remove the frost from the coils 103 and 104 it is only necessary to close valve 108 and open valve 107 whereupon pump 100 will circulate bilge water through the coils and since this water is of relatively high temperature the frost will be melted therefrom. During this operation it is not desirable that the water circulated through the coils be discharged into the brine tank 82 since this would dilute the brine solution therein. Consequently, there is provided in the return line 105 a valve 109 which may be closed during defrosting to prevent discharge of water in the tank 82.

In order that the water circulating through the coils may be discharged overboard a discharge pipe 110 is connected to the return line 105. The pipe 110 has a valve 111 therein which, when opened, will permit discharge of the defrosting water overboard.

Likewise, brine pump 100 may be used to circulate sea water through coils 103 and 104 for defrosting purposes and accordingly in order to carry out this operation a pipe 112 may be connected to the intake conduit 101, pipe 112 leading to the exterior of the ship below the water line. Pipe 112 is also provided with a valve 113 which need only be opened when it is desired to take in sea water through pump 100. During this operation, of course, valve 107 in pipe 106 is closed, the remainder of the operation being the same as when bilged water is being used for defrosting.

Brine pump 100 may also be used for pumping out the bilges of the ship and in this case valve 107 in pipe 106 would be opened while valve 108 in intake 101 is closed. This water is discharged through discharge line 102 and an overboard pipe 114 having a valve 115 therein. In order to prevent flow of this water through the coils 103 and 104 a valve 116 is provided in the discharge line 102.

It will thus be seen that by the above described arrangement there has been provided means for obtaining maximum utility from a single pump and by a proper arrangement of the various valves on a manifold or control board. All of these operations may be conveniently con-

trolled from a central operating station and it is also apparent that use of the brine pump for the various other functions will in no way impair its efficient operation in circulating cold brine through the coils in the storage rooms.

In order that melted frost or other water present in the cold storage rooms may be drained off, there is provided a drainage opening 117 in the deck of the lower storage room 57 opening 107, communicating with the bilge 88 so that water may be drained thereinto.

From the foregoing it will be readily understood that by the present invention there is provided a mobile ice manufacturing plant which includes the manufacture of ice in any desired size; the plant is self-contained requiring no outside source of power; and it is adapted to use water either fresh, salt or brackish. Further it is a complete unit in itself; it can be moved from one location to another with ease. The ice plants are all driven from the power plant of the vessel. The relatively warm water of one of the ice plants is employed for defrosting the surface of the ice cans sufficiently to permit the ice to be dislodged. The refrigeration systems consisting of the main and the two auxiliary plants will not be prevented from operating due to their not being level because of the fact that the vessel is provided with an automatic leveling system which is believed to be new in this particular art.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A mobile ice manufacturing plant comprising a vessel having ice production and storage compartments and port and starboard bilge compartments, a conduit connecting said bilge compartments and providing communication therebetween, a motor driven reversible pump in said conduit, a refrigerating system including refrigerating coils located in said storage compartment for maintaining desired conditions of temperature therein, a power plant for operating said refrigerating system, a relatively shallow elongated brine tank of a width substantially corresponding to that of the vessel and extending lengthwise thereof, means for conveying cans of ice from the brine tank to the ice storage compartment, a pump for circulating refrigerant from the brine tank through the refrigerating coils in the ice storage compartment, and automatic leveling mechanism including a pendulum control and opposed contact members for making and breaking an electrical circuit in accordance with the position of the vessel, said motor driven reversible pump being operatively connected to said pendulum control means and opposed contact members for producing movement of water between the port and starboard bilge tanks for stabilizing the vessel to maintain a substantially even level of liquid in the brine tank.

2. A mobile ice manufacturing plant comprising a vessel having ice production and storage compartments and port and starboard bilge compartments, a conduit connecting said bilge compartments and providing communication therebetween, a motor driven reversible pump in said conduit, a refrigerating system including refrigerating coils located in the ice storage compartment

ment, a power plant for operating said refrigerating system, a relatively shallow elongated brine tank of a width substantially corresponding to that of the vessel and extending lengthwise thereof, a hoist for conveying cans of ice from the brine tank to the ice storage compartment, temperature modifying means associated with the ice storage compartment for melting ice in the cans sufficiently to permit the ready removal of said ice and the dumping thereof in said storage compartment, a brine pump for circulating brine from the brine tank through said refrigerating coils for maintaining desired conditions of temperature in the storage compartment, a conduit system for selectively pumping liquid from the brine tank, from the bilge compartments and from the sea through said refrigerating coils for selectively refrigerating and heating said coils for defrosting purposes, and automatic leveling mechanism including a pendulum and spaced opposed contact members for making and breaking an electrical circuit in accordance with the position of the vessel, said motor driven reversible pump being operatively connected with said pendulum control and opposed contact members for producing movement of water between the port and starboard bilge tanks for stabilizing the vessel to maintain a substantially even level of liquid in said brine tank.

3. A mobile ice manufacturing plant comprising a vessel having walls defining ice production, unloading and storage compartments and port and starboard bilge compartments, a conduit connecting said bilge compartments and providing communication therebetween, a motor driven reversible pump in said conduit, a refrigerating system including refrigerating coils located in said ice unloading and storage compartments, a power plant for operating said refrigerating system, an elongated relatively shallow brine tank of a width substantially corresponding to the width of the vessel and extending lengthwise thereof, a dip tank in said unloading compartment, a hoist for conveying cans of ice from said brine tank to said dip tank, temperature modifying means associated with said dip tank for melting ice in the cans sufficiently to permit the ready removal of ice therefrom and dumping of said ice into said storage compartment, a brine pump for circulating brine from the brine tank through the refrigerating coils for maintaining desired conditions of temperature in said unloading and storage compartments, a conduit system for selectively pumping liquid from the brine tank, from the bilge compartments and from the sea through the refrigerating coils for selectively refrigerating and heating said coils for defrosting purposes, and automatic leveling mechanism including a pendulum control and opposed contact members for making and breaking an electrical circuit in accordance with the position of the vessel, said motor driven reversible pump being operatively connected with said pendulum control and opposed contact members for producing movement of water between said port and starboard bilge tanks for stabilizing the vessel to maintain a substantially even level of liquid in said brine and dip tanks.

4. A mobile ice manufacturing plant comprising a vessel having walls defining port and starboard bilge compartments and ice production, storage and unloading compartments, a refrigerating system including a compressor and an evaporative condenser, a ship's power plant for

operating said refrigerating system, an elongated relative shallow brine tank of a width substantially corresponding to that of the vessel and extending lengthwise thereof, an operating platform located at a higher elevation rearwardly of said brine tank, at least one dip tank and ice can dump on said platform, a hoist movable transversely and longitudinally of said brine tank for conveying cans of ice from the brine tank to the dip tank and then to the can dump, temperature modifying means associated with the dip tank for melting ice in the cans sufficiently to permit ready removal and dumping thereof into the can dump, means for directing ice from the dump into an unloading and storage compartment located in substantially the same horizontal plane as the brine tank and including slide-ways for providing an indirect path for lowering the ice gradually into a second storage compartment, an ice crusher in said second storage compartment, a conveyor for transferring crushed ice from the second storage compartment upwardly into the ice unloading and storage compartment, means for discharging ice from said cans directly into said unloading and storage compartment for supplementation of the crushed ice received therein from the second storage compartment, a brine pump for circulating brine from said brine tank in contact with refrigerating coils disposed in the unloading and storage compartments for maintaining refrigerated conditions of temperature in said compartments, a conduit system for selectively pumping liquid from the brine tank, from the bilge compartments and from the sea through the refrigerating coils for selectively refrigerating and heating said coils for defrosting purposes, a conduit connecting the port and starboard bilge tanks and providing communication therebetween, a motor driven reversible pump in said conduit, and automatic leveling mechanism including a pendulum control and spaced opposed contact members for making and breaking an electrical circuit in accordance with the position of the vessel, said motor driven reversible pump being operatively associated with said pendulum control and opposed contact members for producing movement of water between said port and starboard bilge tanks for stabilizing the vessel to maintain a substantially even level of liquid in said brine and dip tanks.
